DOOR OPERATOR

John E. W. Fogal, deceased, late of Quincy, Ill.,
by Anna E. Fogal, executrix, Quincy, Ill., as-
signor to Anna E. Fogal

Application March 28, 1931, Serial No. 525,955

11 Claims. (Cl. 268—19)

The invention relates to door constructions of types too large to be manually opened and closed, and includes among its objects and advantages an increase in operating facility and a decrease 5 in the cost and complexity of the operating mechanism for one or more doors.

In the accompanying drawings:

Figure 1 is a side elevation of a door operating mechanism;

Figure 2 is a longitudinal sectional view of a portion of the structure shown in Figure 1;

Figure 3 is a sectional view taken substantially along the line 3—3 of Figure 1;

Figure 4 is a sectional view taken along the line 4—4 of Figure 1;

Figure 5 is a sectional view taken along the line 5—5 of Figure 1;

Figure 6 is a diagrammatic view showing a plurality of doors associated with a single source of power; and

Figure 7 is a view showing a wiring diagram for the electrical equipment.

In the embodiment selected to illustrate the invention use is made of doors 10 (see Fig. 6) connected with drums 12 upon which the doors may be wound through the medium of door operating mechanisms 14 which are associated with a motor 16 and a speed reducer 18. A main drive shaft 20 extends from the speed reducer 18 to the mechanisms 14. Each of the mechanisms may be operatively connected with the main drive shaft for opening and closing its respective door 10, which is of the rolling type.

Push buttons 22, 24, and 26 representing "up", "down" and "stop" functions, respectively, are associated with each of the doors for controlling the electrical circuit through the motor 16 and its associated electrical devices identified in the mechanisms 14. When the button 22, associated with a given door, is pressed, that door will be wound upon its respective roll 12. Pressure upon the button 26 will result in a reverse movement of the door, and pressure upon the button 24 will of course stop the movement of the door in either direction.

The mechanisms 14 are all identical in construction, and each mechanism comprises a hanger body 28 (see Fig. 1) having recesses 30 and 32 for receiving a roller bearing 34 and a thrust bearing 36 respectively. A central opening 38 places the recesses 30 and 32 in communication with each other so that a sleeve 40 may be associated with the bearings 34 and 36. The sleeve 40 is loosely mounted upon the main drive shaft 20.

A plate 42 is secured to one end of the hanger body 28 by means of screws 44 for holding the bearing 34 in place. A sealing disk 46, which fits snugly upon the sleeve 40, is positioned between the plate 42 and the bearing. A similar plate 48 is secured to the opposite end of the hanger body for holding the thrust bearing 36 in place. Screws 50 secure the plate 48 to the hanger body.

One end of the sleeve 40 is provided with a fixed gear 52 arranged in mesh with a companion gear 54 associated with one of the drums 12.

The sleeve 40 is provided with a shoulder 56 which bears against the thrust bearing 36 and upon which a gear 58 is positioned. The gear is fixed to a second shoulder 60 through the medium of screws 62. The shoulder 60 is formed integrally with a clutch element 64. This element is provided with a clutch facing 66 which may be engaged by a movable clutch element 68 slidably mounted upon the drive shaft 20 by means of 20 keys 71. The clutch element 68 rotates with the drive shaft 20 and causes a rotation of the sleeve 40 when it is moved into frictional engagement with the clutch element 64.

Means for moving the clutch element 68 comprises a clutch lever 70 having a bifurcated end 72 pivotally secured between lugs 74 associated with a fulcrum member 76. The fulcrum member (see Fig. 5), is provided with an offset portion 78 having an opening 80 for loosely receiving the main drive shaft. The ends of the fulcrum member are provided with openings 82 for receiving supporting bolts 84 (see Figs. 1, 3, and 4). One end of each of the bolts 84 is rigidly secured to the fulcrum member by nuts 86 (see Fig. 1). 35 The opposite ends of the bolts pass through openings 88 in lugs 90 formed integrally with the hanger body 28 (see Figs. 1 and 3). Nuts 92 rigidly secure the bolts 84 to the lugs 90.

A clutch bearing 94 is mounted upon the drive shaft 20 between the clutch element 68 and the bifurcated end 72 of the lever 70 (see Figs. 1 and 2). The bearing retainer 96 is provided with lugs 98 to which the bifurcated end 72 of the clutch lever is pivotally connected as at 100. 45

Movement of the lever 70 from the full line position shown in Figure 1 to the dotted line position causes the bearing 94 to move the clutch member 68 into frictional engagement with the clutch element 64 for locking the sleeve 40 to the drive shaft 20. The sleeve is freed from the drive shaft 20 as soon as the clutch lever moves back to its full line position.

In Figure 1 is shown the upper end of the lever as being connected with a bolt 102 which in 55

turn is connected with a movable bar 104 forming a part of a solenoid 106 mounted upon an extension 108 cast integrally with the hanger body. The bolt 102 passes through an opening 5 110 in the end of the lever and is provided with a nut 112. A spring 114 is mounted upon the bolt 102 and bears against the nut 112 and a washer 116 which is positioned adjacent a curved portion 118 on one side of the lever 70. The bolt 10 10 is pivotally connected with the bar 104 by means of a pin 120 so that freedom of action is obtained between the bolt, the bar 104, and the lever 70, during the shifting of the lever from one position to the other. The lever is pulled in the 15 direction of the solenoid whenever the latter is energized.

One end of the hanger body 28 is formed with an integral platform 122 for supporting a limit switch 124. The switch is secured to the platform through the medium of screws 126. A shaft 128 associated with the limit switch extends in the direction of the arm 70 and carries a fixed gear 130 arranged in mesh with the gear 58. The gear 58 rotates with the sleeve 40 so that 20 the limit switch 124 is operated whenever the sleeve is moved.

Movement of the lever 70 operates a brake 132 for braking or releasing the clutch element 64. The brake band comprises members 134 (see 30 Fig. 4) provided with brake lining 136 arranged to engage the shoulder 60. One end of each of the members is provided with an opening for receiving a bolt 138 upon which a spring 140 is mounted. The spring bears against the ends of 35 the members 134 for holding the parallel ends yieldingly yet firmly in contact with the head 142 of the bolt and a nut 144 upon the latter. The opposite ends of the members 134 are bent to provide substantially parallel portions 146 40 having openings through which a bolt 148 passes. The bolt also passes through openings 150 in the end of a pair of arms 152 which are integrally formed with the hanger body 28.

Springs 154 are positioned upon the bolt 148 45 between the arms 152 and the portions 146. A cam 156 is loosely mounted upon the bolt 148 and is provided with cam surfaces 158 arranged in contact with similar cam surfaces 160 upon companion cam members 162 attached to the 50 portions 146 of the brake band. Rotation of the cam 156 in a counterclockwise direction as when viewing Figure 1 causes the members 134 to be spread and release the sleeve 40. The springs 154 move the members 134 in the direction of 55 each other for braking the sleeve 40.

In Figure 1 is shown the cam 156 as having an arm 164 connected with the lever 70 through the medium of a link 166. It will thus be seen that the clutch is released whenever the solenoid is 60 energized. The spring 114 upon the bolt 102 forms a cushion between the bar 104 and the arm.

The hanger body 28 is provided with enlarged 65 portions 168 upon its side (see Fig. 3) having openings 170 therethrough for receiving the lower ends of bolts 172 having their upper ends secured to a supporting structure 174. The ends of the bolts passing through the supporting structure may be threaded for receiving nuts 176 70 whereby the hanger body may be raised or lowered and firmly secured in its adjusted position. The enlarged portions 168 are slit as at 178 so that the ears 180 which are a part of the enlarged portions may be moved together by means 75

of bolts 182 for firmly retaining the bolts 172 within the openings 170.

In Figure 7 is shown a wiring diagram for the motor 16 and its associated electrical equipment. The motor is of the three-phase type and 5 is provided with conductors L₁, L₂, and L₃, which lead to a source of current. A reversing magnetic switch 184 comprising elements U and D representing "up" and "down" functions, respectively, is associated with the conductors L₁, L₂, and L₃. 10 Each of the elements comprises contacts 1, 2, and 3, which move as a unit when their respective coils 186 and 188 are energized. Conductors 190, 192, 194, 196, 198, and 200 are connected with the conductors, L₁, L₂, and L₃, and associated with the D element. A solenoid brake 202, 15 associated with the motor 16, is connected with the conductors 198 and 200.

The wiring diagram illustrated in Figure 7 is suitable for a two-door installation. Two 20 groups of push buttons 22, 24, and 26, are shown. These groups are indicated at "A" and "B", and the description at the present time will be confined to group "A". When the operator desires to raise one of the doors, the push button 22 25 for that door is pressed. Movement of the switch 22 into engagement with contacts 1—3 completes a circuit from L₃ through conductors 204 and 206, 4—2 of the stop push button 26, conductor 220, 1—3 of push button 22, conductor 224, 2—4 of push button 24, conductor 208, coil 210, contact 1 of the limit switch 124, contact 1 of an interlock switch 205, conductor 203 to L₂. The coil 210 is associated with an element 212 having contacts 1, 2, and 3, comprising 30 the up reversing relay. This relay is closed when the coil 210 is energized.

As soon as the up relay is closed, a circuit through the solenoid 106 is closed as follows: 35 conductors L₃, 204, and 214, contact 1 of the up relay, conductors 216 and 218, solenoid 106, and conductors 203 and L₂. The brake 132 for the individual door is released as soon as the sole- 40 noid is energized.

The push buttons 22 and 24 are of the momen- 45 tary contact type, and for this reason a sealing circuit is employed which is closed as soon as either reversing switch 212 or 238 is closed. The sealing circuit is closed as follows when the push button 22 is pressed: conductors L₃, 204, 206, 4—2 50 of the stop push button 26, conductor 220, contact 2 of the up reversing relay, conductors 222 and 224, 2—4 of the down switch, conductors 208, 203, and L₂. Thus it will be seen that the circuit established by pressing the push button 22 will 55 remain closed even though the push button is released.

The circuit through the motor 16 is closed as follows: conductors L₃, 204, and 214, contact 3 of the up reversing relay, conductor 226, coil 186 of 60 the reversing magnetic switch 184, conductors 228, 203, and L₂. The energized coil 186 moves the U element for closing the circuit through the motor. A coil 230 is associated with contact 2 of the interlock switch. The coil is connected with 65 conductor 203 and conductor 232 connected with the conductor 226. The contact 2 of the interlock switch is opened when the coil 230 is energized so that all down circuits remain open while the motor 16 is rotating in an up direction. The 70 coil 230 is energized simultaneously with the coil 186.

Contact 1 of the limit switch 124 is opened 75 as soon as the door has reached its open position for opening the circuit through the motor 16 and

the solenoid 106. The brake 132 (see Fig. 1) frictionally engages the shoulder 60 for braking the sleeve 40 as soon as the solenoid is deenergized.

The open door is closed by pressing the push button 24. When the button is pressed, the following circuit is closed: conductors L₃, 204, and 206, 4-2 of the push button 26, 1-3 of the push button 24, conductor 234, 4-2 of the push button 22, conductor 236, coil 237 of the down reversing relay, contact 2 of the limit switch, contact 2 of the interlock switch, and conductors 203 and L₂. The coil 237 is associated with the element 238 having contacts 1, 2, and 3. The down reversing relay is closed when the coil 237 is energized.

15 The sealing circuit is closed as follows: conductors 204 and 206, 4-2 of the stop switch 26, conductor 220, contact 2 of the down reversing relay, conductors 248 and 234, 4-2 of the push button 22, and conductors 236, 203, and L₂.

20 The circuit through the solenoid 106 is closed as follows when the down reversing relay is closed: conductors L₃, 204, and 214, contact 1 of the down reversing relay, conductors 216 and 218, solenoid 106, and conductors 203 and L₂. The circuit through the motor is established in the following manner: conductors L₃, 204, and 214, contact 3 of the down reversing relay, a conductor 242, coil 108, conductor 244 which is connected with conductors 203 and L₂. The element D is moved 30 for closing the contacts for the motor 16 when the coil 108 is energized.

A coil 246 is associated with the contact 1 of the interlock switch. The coil is connected with the conductor 203 and a conductor 248, which, in turn, is connected with the conductor 242. The coil 246 is energized simultaneously with coil 108 so that all up circuits are broken during the operation of the motor 16 for closing the door.

It will be noted that the initial and the sealing 40 circuits for button 22 pass through the contacts for buttons 24 and 26; also that the initial and sealing circuits for button 24 pass through the contacts for buttons 26 and 22. Therefore, operating the stop button 26 will incapacitate both the 45 up and down buttons and always stop the door. Similarly, pressing either button 22 or 24 when the door is moving in the opposite direction will first open the circuits for the other button and stop the door, and then start it in the new 50 direction.

The conductors 208, 218, 226, 242, and 236, of the group "B" are respectively connected with the conductors 208, 218, 226, 242, and 236, of the group "A". The operation of group "B" is identical with group "A". It is obvious that the circuit may be extended to accommodate any number of doors within the capacity of the motor 16 by merely adding groups "C", "D", etc.

The doors 12 may be individually opened or 60 closed. Any number of the doors may be simultaneously opened or closed by pressing upon their respective push button 22 or 24. All the doors may be simultaneously opened or closed through the medium of a master switch 250 which is associated with a conductor 252 connected with the conductor L₃. A conductor 254 is connected with the conductors 208, while a conductor 256 is connected with the conductors 236. When the master switch is operated for electrically connecting the conductor L₃ with the conductor 254, the up circuits will be closed, so that all the doors are simultaneously opened. When the master switch is moved for electrically connecting the conductor 70 L₃ with the conductor 256, all down circuits will

be closed so that all the doors are simultaneously moved to their closed positions.

As each individual door reaches the limit of its movement, its limit switch 124 will open and open the reversing switch for that door, which disconnects the clutch solenoid 106 for that door and mechanically disconnects the door from the line shaft 20. As long as any door remains short of the end of its movement, at least one individual reversing switch will remain closed, and the 10 motor will continue to operate. When the last door reaches its final position, the opening of the last limit switch will stop the motor.

The solenoid brake 202 is connected with the conductors L₂ and L₁ in such a manner that the 15 brake is released whenever the reversing magnetic switch 184 is energized.

The invention claimed is:

1. The combination with a plurality of warehouse doors of the roll-up type, of a single electric 20 motor, mechanical transmission means in the nature of a drive shaft extending from said motor into proximity with each of said doors, individual mechanical connections associated with each of said doors for connecting and disconnecting 25 that particular door with said transmission means, electrical control means for each individual door, each electrical control means including, first, means for operating said motor to open the door and simultaneously connecting 30 said door to said transmission, second, means for operating said motor to close the door and simultaneously connecting said door to said transmission, and third, means for stopping said motor and simultaneously disconnecting said door from 35 said transmission, said mechanical connections including brake means for holding said door against movement when it is not connected with said transmission; interlocking connections between the electrical means for all said doors 40 whereby when the motor is operating to open, any door not entirely open may be mechanically connected to said transmission, and whereby when the motor is operating to close, any door not entirely closed may be mechanically connected to said transmission; and individual electrical limit means associated with each door 45 and operative to disconnect said door mechanically at the end of its movement in either direction and to stop said motor when not required 50 for operating some other door.

2. The combination with a plurality of warehouse doors of the roll-up type, of a single electric motor, mechanical transmission means in the nature of a drive shaft extending from said 55 motor into proximity with each of said doors, individual mechanical connections associated with each of said doors for connecting and disconnecting that particular door with said transmission means, electrical control means for each individual door, each electrical control means including, first, means for operating said motor to open the door and simultaneously connecting 60 said door to said transmission, second, means for operating said motor to close the door and simultaneously connecting said door to said transmission, and third, means for stopping said motor and simultaneously disconnecting said door from 65 said transmission, said mechanical connections including brake means for holding said door against movement when it is not connected with said transmission; interlocking connections between the electrical means for all said doors whereby when the motor is operating to open, any door not entirely open may be mechanically 70 connected to said transmission; and individual electrical limit means associated with each door and operative to disconnect said door mechanically at the end of its movement in either direction and to stop said motor when not required 75 for operating some other door.

connected to said transmission, and whereby when the motor is operating to close, any door not entirely closed may be mechanically connected to said transmission; individual electrical limit means associated with each door and operative to disconnect said door mechanically at the end of its movement in either direction and to stop said motor when not required for operating some other door; and master switch means for operating said motor in either direction and simultaneously connecting to said transmission all doors at that time capable of movement in the direction in which the motor is operating.

3. The combination with a plurality of warehouse doors of the roll-up type, of a single electric motor, mechanical transmission means in the nature of a drive shaft extending from said motor into proximity with each of said doors, individual mechanical connections associated with each of said doors for connecting and disconnecting that particular door with said transmission means, electrical control means for each individual door, each electrical control means including, first, means for operating said motor to open the door and simultaneously connecting said door to said transmission, second, means for operating said motor to close the door and simultaneously connecting said door to said transmission, and third, means for stopping said motor and simultaneously disconnecting said door from said transmission, said mechanical connections including brake means for holding said door against movement when it is not connected with said transmission; interlocking connections between the electrical control means for all said doors whereby when the motor is operating to open, any door not entirely open may be mechanically connected to said transmission, and whereby when the motor is operating to close, any door not entirely closed may be mechanically connected to said transmission; individual electrical limit means associated with each door and operative to disconnect said door mechanically at the end of its movement in either direction and to stop said motor when not required for operating some other door; and master switch means for operating said motor in either direction and simultaneously connecting to said transmission all doors at that time capable of movement in the direction in which the motor is operating; each individual electrical control means including momentary push button switches for up and down, and holding circuits for maintaining the operation as the push button switch is released; said holding circuits being controlled by said second means for stopping, which second means is also a push button switch.

4. The combination with a plurality of doors arranged in a row and generally parallel to the plane of the row, of a line shaft parallel to said row and extending past all said doors, a motor for driving said line shaft, individual electrical control means adjacent each door for connecting said door to said shaft and for energizing said motor, whereby said motor is inactive except when at least one of said doors is being operated, said control means including electric wiring between said motor and all said control means arranged upon actuation of any door in one direction to render inoperative the control means for operating any other door in the opposite direction, but leaving operative the control means for operating any other door in the same direction, and a master switch at one point for operating all the doors simultaneously in either direction.

5. The combination with a plurality of doors arranged in a row and generally parallel to the plane of the row, of a line shaft parallel to said row and extending past all said doors, a motor for driving said line shaft, and individual electrical control means adjacent each door for connecting said door to said shaft and for energizing said motor, whereby said motor is inactive except when at least one of said doors is being operated, said control means including electric wiring between said motor and all said control means arranged upon action of any door in one direction to render inoperative the control means for operating any other door in the opposite direction. 10

6. The combination with a plurality of doors arranged in a row and generally parallel to the plane of the row, of a line shaft parallel to said row and extending past all said doors, a motor for driving said line shaft, individual electrical control means adjacent each door for connecting said door to said shaft and for energizing said motor, whereby said motor is inactive except when at least one of said doors is being operated, and a master switch at one point for operating all the doors simultaneously in either direction. 20

7. The combination with a plurality of doors arranged in a row, of a line shaft extending past all said doors, a motor for driving said line shaft, individual electrical control means adjacent each door for connecting said door to said shaft and for energizing said motor, whereby said motor is inactive except when at least one of said doors is being operated, and a master switch at one point for operating all the doors simultaneously in either direction, each said individual control means rendering inoperative all other control means for operating any door in the opposite direction, but leaving operative the control means for operating any other door in the same direction. 30

8. The combination with a plurality of doors; of a line shaft; a reversible motor for driving said line shaft; individual means for connecting each door to said line shaft to be opened or closed according to the direction of motion of said line shaft; and manual control devices for each door including a first device for connecting said door and energizing said motor to open the door, a second device for connecting said door and energizing said motor to close the door, and a third device for disconnecting said door and motor; said energizing devices being interconnected so that actuation of any energizing device renders inoperative only those of the energizing devices of the other doors that would operate the motor in the other direction. 40

9. The combination with a source of current and a single motor adapted to be actuated thereby in either direction, of a plurality of sets of controls, each set comprising three push button controls, one for driving the motor in one direction, identified as "up", another for driving the motor in the opposite direction, identified as "down", and a third for stopping the motor, all three push button controls having contacts operative to complete a circuit when the controls are inactive, and the "up" and "down" controls having contacts operative to complete a circuit when the controls are active, each active circuit being wired in series through the inactive contacts of each of the other push buttons, a movable door associated with each set of controls, and unitary means actuated by either the "up" or the "down" button of the associated set, for 50

mechanically connecting said door to said motor to be actuated thereby.

10. The combination with a source of current and a single motor adapted to be actuated thereby in either direction, of a plurality of movable doors, a plurality of sets of controls, each set associated with one of said doors and comprising three push button controls, one for driving the motor in one direction, identified as "up", another for driving the motor in the opposite direction, identified as "down", and a third for stopping the motor, all three push button controls having contacts operative to complete a circuit when the controls are inactive, and the "up" 10
15 and "down" controls having contacts operative to complete a circuit when the controls are active, each active circuit being wired in series through the inactive contacts of each of the other push buttons, each active circuit closing a relay switch, 20
25 each relay switch closing additional circuits as follows, a first circuit for mechanically connecting said motor with the associated door, a second sealing circuit parallelling that portion of the original active circuit completed by the push button switch, a third circuit actuating the motor in the desired direction, and a fourth circuit partly in parallel with the third circuit for disconnecting and rendering inoperative those of the active circuits of all other control sets, which 30 would operate to run the motor in the opposite direction.

11. The combination with a source of current and a single motor adapted to be actuated thereby in either direction, of a plurality of movable doors, a plurality of sets of controls, each set associated with one of said doors and comprising three push button controls, one for driving the motor in one direction, identified as "up", another for driving the motor in the opposite direction, identified as "down", and a third for stopping the motor, all three push button controls 10
15 having contacts operative to complete a circuit when the controls are inactive, and the "up" and "down" controls having contacts operative to complete a circuit when the controls are active, each active circuit being wired in series through the inactive contacts of each of the other push buttons, each active circuit closing a relay switch, 20
25 each relay switch closing additional circuits as follows, a first circuit for mechanically connecting said motor with the associated door, a second sealing circuit parallelling that portion of the original active circuit completed by the push button switch, a third circuit actuating the motor in the desired direction, and a fourth circuit for disconnecting and rendering inoperative those of the active circuits of all other control sets, which 30 would operate to run the motor in the opposite direction.

ANNA E. FOGAL,
Executrix of the Estate of John E. W. Fogal, 30
Deceased.
